HOT AIR FURNACE

Carl Lengyel, Buffalo, N. Y.

Original application December 13, 1939, Serial No. 309,047. Divided and this application July 23, 1940, Serial No. 346,931

1 Claim. (Cl. 126—99)

This invention relates to improvements in a hot air furnace of the type which includes a hollow radiator or drum through which hot gases are conducted from a combustion chamber to a chimney or flue and a housing forming an air chamber and having a lower upright wall which surrounds the side of the radiator and adjacent parts of the heating apparatus and a top or dome which extends inwardly from the side wall over the entire radiator and is separated throughout its entire width from the upper side of the radiator by an intervening air space.

In the operation of such furnaces as heretofore constructed the hot gases passing upwardly from the combustion chamber first engage with the central part of the housing top or dome and then are deflected laterally thereby in the air space between the upper side of the radiator and to the underside of the dome toward the air outlets formed in the marginal parts of the dome through which they escape to the chimney or flues leading to the outer atmosphere.

Inasmuch as the gases upon rising from the combustion chamber are in their hottest condition and therefore operate with the greatest intensity on the central part of the upper side of the radiator it follows that the air immediately above this part of the radiator is also heated to the greatest extent. In prior furnaces undue heating of the air in the room immediately above the central part of the dome has been prevented by making this central part of the housing dome of downwardly dished form and filling the same with sand which operates as an insulator to prevent excess heating of the respective part of the housing dome and the external air adjacent thereto.

This construction is objectionable inasmuch as a dead body of air is constantly present between the central parts of the radiator and the housing dome which, owing to its low heat conducting capacity, interferes with the transference of heat from this part of the radiator to the stream of air flowing upwardly from the marginal parts of the radiator through the corresponding parts of the air space between the radiator and housing dome to the air outlets of the latter, and therefore reduces the efficiency of the furnace accordingly.

It is the purpose of this invention to provide a hot air furnace of this character with simple and efficient means whereby the dead air space immediately above the central part of the radiator is eliminated and heat from this part of the latter is transferred to the stream of air passing

through the annular space between the marginal parts of the radiator and the housing dome, thereby not only effecting a saving in fuel but also increasing the speed of the air which is being heated and enabling rooms to be warmed more rapidly than has been possible heretofore.

This is a division of United States patent application Serial No. 309,047, filed December 13, 1939, patented August 27, 1940 under No. 2,212,666.

In the accompanying drawing:

Fig. 1 is a vertical section of a hot air furnace embodying one form of this invention.

Fig. 2 is a horizontal section, on an enlarged scale, taken on line 2—2, Fig. 1.

Fig. 3 is a fragmentary vertical section, on an enlarged scale, taken on the correspondingly numbered line in Fig. 2.

In the following description similar characters of reference indicate like parts in the several views of the drawing.

Although this invention may be embodied in hot air furnaces which may vary in details of construction that shown in Fig. 1 is suitable and comprises a heating apparatus having a lower pit 10, a fire pot 11 which is arranged above the pit and in which the fuel is burned, a combustion chamber 12 which receives the gases from the fire pot and in which the combustion of the same is completed, and a hollow radiator or drum which is arranged above the combustion chamber and which has a central section 13 constructed in the form of a cap having a closed crown or head 14 and an open lower end through which it receives the hot gas from the upper end of the combustion chamber, and an annular heat distributing channel 15 which surrounds said cap-shaped central section 13 and is connected on its inner side with the side wall 16 of the radiator cap by a radial flue 17, while its outer side is provided with a pipe or outlet 18 for the smoke or products of combustion which are delivered to a chimney or flue leading to the outer atmosphere.

When burning hard fuel, such as wood or coal, a grate 19 is employed between the fire pot 11 and the pit and the latter in this case serves to receive the ashes of the burnt fuel, but if a fluid fuel is burned in the fire pot, such as oil or gas, then the grate may be omitted.

An air chamber or jacket is formed around the side of the heating apparatus and over the upper marginal part of the same which is adapted to receive the air to be heated and conduct the same to pipes leading to the places to be heated. This air chamber is formed by a hous-

ing or jacket comprising a lower tubular body or upright wall section 20 of circular form surrounding the side of said ash pit, fire pot, combustion chamber and radiator channel but spaced therefrom and having an air inlet 21 on its lower part, and an upper annular top or dome section 22 extending inwardly from the upper end of the body or side wall 20 and overhanging the marginal part of said radiator but spaced therefrom and provided with one or more air outlets 23 through which the hot air is discharged from the air chamber and then conducted by suitable piping or conduits to the rooms to be heated.

The improvement forming the subject of this invention consists generally of deflecting means which extend from the top of the housing to the upper side of the radiator so as to avoid the formation of a dead air space between the central part of the housing top and the central part of the radiator, thereby compelling all of the air which enters the lower part of the air jacket to flow in the form of a live stream upwardly along the exterior of the heating apparatus and to the hot air outlets of the housing top, whereby the flowing speed of the air is increased and the rooms which are served will be heated more rapidly. The air deflecting means for accomplishing this purpose may be varied, those shown in Figs. 1, 2 and 3 being one form which is suitable and constructed as follows:

The numeral 24 represents the air deflector which is constructed of sheet metal in the form of a downwardly tapering tube or cone which is arranged between the central parts of the radiator and the housing dome. The latter is provided with a central opening 25 forming an inner annular edge thereon to which the upper large end of the deflector is secured in any suitable manner. The lower small end of the deflector is arranged over the marginal part of the central cap 13 of the radiator and is provided with an inturned flange 26 resting on the radiator dome. The crown 14 of the radiator is provided on its upper side with a marginal upstand-

ing rib or flange 27 and the flange 26 of the deflector is arranged around this rib. The space within the deflector is filled with heat insulating material 28, such as rock wool or mineral wool, for preventing radiation of heat from the central part of the radiator to the external air immediately above the same and thus causing the deflector 24 to operate as the sole means which transfer heat from the central part of the radiator to the annular body of air which surrounds the deflector within the housing and thereby causes the air to be heated more efficiently and economically.

This form of deflector is more particularly suited for use in a heating apparatus of this character when the furnace and deflector are both made in a factory and assembled as a completed unit when put on the market inasmuch as the parts can be made of a definite size at this time and accurately fitted to each other without requiring allowance for any adjustment of the parts relative to each other.

This air deflector is very simple in construction and low in cost and its use effects a considerable economy in fuel consumption and expedites the heating operation.

I claim as my invention:

A hot air furnace comprising a combustion chamber in which the hot gases rise, a hollow radiator arranged above the combustion chamber and receiving the hot gases therefrom and provided on the central part of its upper side with an annular rib, a housing forming an air chamber around said combustion chamber and radiator and having a lower upright body and an upper annular top which overhangs the marginal part of said radiator and which has an air outlet, a deflector of downwardly tapering form having its upper end connected with the inner edge of said annular top and having its lower end engaging with the top of said radiator around said rib, and an insulating filling arranged within said deflector.

CARL LENGYEL.
